Primary Examiner — Kendra Leslie Hamilton

(74) Attorney, Agent, or Firm — Thompson Coburn LLP

(57) **CLAIM**

The ornamental design for a nipple as shown and described.

DESCRIPTION

FIG. 1 is a first perspective view of the nipple of my new design.

FIG. 2 is a second perspective view of the nipple of FIG. 1.

FIG. 3 is a front side view of the nipple of FIG. 1.

FIG. 4 is a back side view of the nipple of FIG. 1.

FIG. 5 is a right side view of the nipple of FIG. 1.

FIG. 6 is a left side view of the nipple of FIG. 1.

FIG. 7 is a top view of the nipple of FIG. 1; and,

FIG. 8 is a bottom view of the nipple of FIG. 1.

The broken lines in the drawings are included for the purpose of illustrating unclaimed features and form no part of the claimed design.

1 Claim, 4 Drawing Sheets
